[57] CLAIM

The ornamental design for a one story dwelling, as shown and described.

DESCRIPTION

FIG. 1 is a front elevational view of a one story dwelling showing my new design.

FIGS. 2, 3 and 4 are rear elevational, left side elevational and right side elevational views, respectively, thereof, and

FIG. 5 is a perspective view showing the roof, front and left side of my said design, the roof being surfaced with gravel.
